UNITED STATES PATENT OFFICE.

EDWARD S. EVANS, OF DETROIT, MICHIGAN.

METAL DOUBLE-DECKING BUCK FOR AUTOMOBILES.

1,395,225.

Specification of Letters Patent. Patented Oct. 25, 1921.

Application filed September 8, 1919. Serial No. 322,555.

To all whom it may concern:

Be it known that I, EDWARD S. EVANS, a citizen of the United States of America, residing at Detroit, in the county of Wayne and State of Michigan, have invented certain new and useful Improvements in Metal Double-Decking Bucks for Automobiles, of which the following is a specification.

In the automobile industry, a manner of shipping automobiles safely upon railway box and flat cars constitutes a considerable undertaking usually quite expensive. Automobiles have been heretofore shipped by tilting the same upon flat cars as well as 10 double decking the automobiles in box cars, expensive wooden staging and rigid bridge work being employed. My invention contemplates the provision of metal bucks which are strong and inexpensive being capable of repeated use for supporting automobiles in elevated positions upon cars for safe shipment, the structure being such as to bring the entire weight of the load upon the bottom of the car with no screws or bolts 20 liable to shear-off, permitting the automobile to fall. My invention is readily disassembled when not in use being compactly folded for return shipment.

By means of my invention, an automobile may be safely maintained elevated by its hubs alone or on its axles without injury to any part of the automobile, even the enamel upon the hubs being protected, without the necessity of removing the hub caps 30 from said hubs. Broadly considered, these objects are accomplished by bearing plates in which the hubs are fitted for close engagement without play or any chance at wobbling, suitable supporting legs being 40 fitted to the plates in the absence of bolts, screws, or rivets, the lower ends of the legs being secured to the car floor while braces suitably space the plates from the sides of the car, maintaining the plates in position 45 beneath the hubs.

With these general objects in view, the invention consists of the novel combination and arrangement of parts hereinafter more fully described in connection with the accompanying drawings, in which like reference characters designate corresponding parts throughout the several views.

In the drawings,

Figure 1 is an elevational view of the invention with an automobile supported there-

on, with the wall legs shown in vertical section,

Fig. 2 is a front elevation of a side portion thereof with the box car shown in vertical transverse section,

Fig. 3 is an outer elevational view of one of the head plates detached, taken upon an enlarged scale with portions of the supporting legs indicated by broken lines,

Figs. 4 and 5 are diametrical sectional views taken through the head plate substantially upon lines 4-4 and 5-5 respectively,

Fig. 6 is a perspective view of the head plate,

Fig. 7 is a perspective view of a slightly different form of head plate with a flanged receiving socket for the hub cap or axle also serviceable in a two-legged structure,

Fig. 8 is a perspective view of a retaining strap serviceable with the head plates, and

Fig. 9 is a perspective view of an end portion of one of the supporting legs adapted for fitting the head plate.

My invention primarily consists in a trapezoidal head 10 formed of sheet metal having receiving ribs 11 for suitable supporting legs 12, the ribs being struck up from one side of the plate. The ribs 11 correspond in number to the number of legs 12 employed, three legs being preferable for heavy weight automobiles as shown in Fig. 1 employing the plate 10, while a similar plate 10' illustrated in Fig. 7 has two similar ribs 11' adapting the same for a two-legged structure for light automobiles.

The outermost ribs 11 are in planes parallel to the adjacent oblique edges 13 of the plate 10 and are adapted for reception within longitudinal slots 14 of the outer legs 12 of the buck or horse whereby said legs are divergently arranged. The intermediate rib 11 is perpendicular to the lower edge 15 of the plate 10 and is received in the slot 14 in the upper end of the middle leg 12 whereby the middle leg is positioned upright in the same vertical plane as the adjacent axle of the automobile such as 16 when in its supported position. The legs 12 being preferably tubular are connected together by horizontal braces 17 also preferably tubular with securing means 18 extending through the legs and flattened portions of said braces, the buck head 10 being readily adaptable for loading automobiles supported either by the axles, spindles or hubs.

A U-shaped socket or saddle 19 is struck out of the shorter top edge 20 of the plate 10 with a laterally projecting flange 21 at the same side of the plate as the ribs 11 formed for receiving and fitting the hub cap 22 of any particular make of automobile which it is desired to support in an elevated position. The socket 19 receives the hub 22 of the automobile wheel 23 so as to flatly mount or engage the hub 22 upon the flange 21 of the plate 10, these flanges being closely fitting, preventing wobbling and all relative movements between the wheels 23 and plates 10 when in use. The saddle 19 may support the axle or spindle of the automobile if desired.

It has, however, been found very desirable in this art to provide mounting means in which the hub or hub flange of the automobile wheel could be received, thus bringing all of the supporting structure outside the wheels. This has been found difficult to accomplish owing to danger of damaging the hubs. With my device, however, the hubs have a relatively wide and accurate bearing in the sockets, and the plates being inwardly inclined toward opposite sides of the automobile, all direct vertical thrust upon the hubs, due to the weight of the automobile is relieved, the thrust due to such weight being inward against the hub flange and eliminating all danger of injuring the hub-caps.

A rectangular recess 24 is countersunk substantially centrally in the plate 10 beneath the socket 19 projecting from the other side of the plate from the socket flange 21, to receive the inner end of a wall leg or arm 25 which is secured horizontally, as by a cleat 26, to the adjacent vertical side wall 27 of the railway car 28. The automobile 16 is elevated adjacent the roof 29 of the car 28 by any convenient means such as a pneumatic jack or chain-falls and a buck positioned with its head 10 beneath the hub 22 of each wheel 23 with the bucks inwardly inclined permitting the lowering of the automobile for seating the hubs 22 into the saddles 19-21 as illustrated in Figs. 1 and 2 of the drawings.

It is understood that a pair of bucks are employed at each side of the car, one pair for the front, and the other pair for the rear. Each buck of the forward pair has its rear-most leg at a greater degree of obliquity than the foremost leg. Similarly, each buck of the rear pair of bucks has its foremost leg at a greater degree of obliquity than the rear legs of these bucks. As a result, foremost legs of the rear pair of bucks will overlap the rear legs of the forward pair of bucks, and these overlapping legs may be secured as by a bolt 30. Floor sockets as 31 receive the lower ends of the legs. The manner of mounting the automobile upon 4 bucks will be apparent from an inspection of the draw-

ings, the legs 12 supporting the entire weight of the automobile 16 by means of the plates 10, the wall legs or arms 25 only serving to maintain the plates 10 accurately spaced from the car sides 27 to receive and hold the hubs 22 in the sockets 19.

Due to the form of the ribs 11 or 11', it will be observed that no further securing means is essential for holding these parts into interengaged position although, if desired, bolts 33 may be used, the ribs having openings 34 and the legs openings 35 for this purpose, and metal straps 36 placed over the hubs and secured by hold fast devices, not shown, positioned through perforations 37 in the plates 10 and perforations 38 through said straps. The hubs 22 being fitted into the saddles 19-21, no injury to the hubs is occasioned by supporting the automobile solely by said hubs. Removing of the automobile wheels 23 is rendered unnecessary and the vehicle is safely suspended against injury for transportation in any suitable form of railway car, it being understood that a second automobile will be secured to the floor 32 between the bucks and beneath the suspended automobile 16.

A two-legged buck is assembled by using the head plate 10' having two-legged attaching ribs 11' and a struck out recess 24' to receive the wall leg such as 25. A flange 39 may be struck out of the plate 10' into which the hub 22 is received projecting through the perforation 40 in the plate 10', the said flange 39 being of the proper contour to receive and closely fit the hub 22 of the automobile 16 to be suspended by the buck. While the forms of my invention herein set forth are believed preferable, minor changes may be made in details of construction as the legs 12 may be solid instead of tubular and of any form capable of detachable connection with the head plates 10. The braces 17 may also be of any other than tubular form as may be desired, while the plates 10 may be of sufficient thickness for forming the flange portions 21 as integral parts of the plates.

When the automobile 16 has been removed from the bucks, the same are separated by removing the bolts 30 and the bucks are then readily taken down and disassembled for shipment by removing the plates 10 from the legs 12 after the bolts 33 have been removed if these bolts are employed. The feet 31 being disconnected from the floor 32 and the arms 25 also removed, the legs 12 and braces 17 may be folded, using the members 18 as pivots. The arms 25 and cleats 26 may be formed of wood and discarded, while the head plates and legs of the bucks being of metal have long life and capable of repeated use in automobile transportation. A great saving of labor, material and expense is accomplished by the provision of my form of

metal mounting bucks, the first expense being reduced as well as liability of breakage and requirement for repairs. An ordinary workman can readily install automobiles for shipment in double deck arrangement by employing these bucks. The buck heads 10 may be also supplied separately as a complete article to be employed by the shipper with any desired form of legs and braces 5 for supporting vehicles with the heads properly positioned beneath either the axles, hubs or spindles thereof.

What I claim as new is:—

1. In an automobile loading means, a supporting port including a mounting means comprising a sheet metal head plate having a laterally extending hub receiving saddle in one edge thereof, and legs removably attached to the plate supportingly projecting from 15 the opposite edge thereof when assembled for use.
2. Automobile loading means comprising a plate of sheet metal having a U-shaped socket in one edge thereof with a laterally 20 extending receiving flange formed as a continuation to the socket, leg attaching ribs on the plate at the same side of the plate as the flange, and legs detachably connected to the said ribs.
3. Means for mounting automobiles in shipping cars comprising a trapezoidal plate of sheet metal having a U-shaped socket in one edge thereof with a receiving flange formed as a continuation to the socket, legs 25 attaching ribs on the same side of the plate, legs detachably connected to the said ribs, said plate having a struck up recess substantially centrally thereof for the reception of a bracing arm when the plate is 30 in use.
4. A buck for the loading of automobiles in freight cars, comprising a sheet metal plate having a flanged socket therein adjacent its upper edge adapted for receiving 35 and fitting the hub of an automobile wheel when the device is in use, and a plurality of upwardly converging supporting legs having their upper ends detachably connected to the lower edge portion of the plate.
5. An automobile buck for the supporting 40

of automobiles in freight cars for shipment comprising a sheet metal plate having a flanged socket in its upper edge adapted for receiving and fitting the hub of a vehicle wheel when the device is in use, divergent 55 ribs extending laterally of the face of said plate, and supporting legs for the plate removably engaging said ribs.

6. An automobile buck comprising a sheet metal plate having a flanged socket therein adapted for receiving and fitting the hub of a vehicle wheel when the device is in use, divergent ribs extending laterally from one 60 face of said plate, and legs having longitudinal slots in their upper ends adapted for 65 the reception of said ribs therein.

7. A load supporting head for automobile bucks comprising a sheet metal plate having a socket formed therein adapted for receiving and closely fitting the hub of a vehicle 70 wheel when the device is in use, laterally extending ribs struck out from said plate, and supporting legs removably telescoping with said ribs.

8. A load supporting head for automobile bucks comprising a plate having a flanged socket formed therein adapted for receiving and closely fitting the hub of a vehicle wheel when the device is in use, laterally-projecting ribs upon said plate, supporting 75 legs removably telescoping with said ribs, said plate having a recess therein at the opposite side thereof from the receiving side of the socket adapted for the reception of a bracing arm.

9. A head for an automobile loading buck, comprising a sheet metal plate adapted to be obliquely disposed with respect to the hub of an automobile wheel and formed with a socket shaped to fit and adapted to 80 receive said hub when so disposed.

10. A sheet metal head plate for an automobile buck, said plate formed with a seat shaped to fit and adapted to receive the hub of an automobile wheel, said plate being 85 also formed with a brace receiving socket, and with leg receiving ribs projecting laterally from the face of the plate.

In testimony whereof I affix my signature.

EDWARD S. EVANS.
